US00D555537S

(12) **United States Design Patent** (10) **Patent No.:** **US D555,537 S**
Portelli (45) **Date of Patent:** **** Nov. 20, 2007**

(54) **BUCKLE GUARD**(76) Inventor: **Charles Portelli**, 2b Kerferd Street, Hampton, VIC (AU) 3198GB 2 307 711 6/1997
GB 2 368 093 4/2002
GB 2 391 900 2/2004(**) Term: **14 Years**(21) Appl. No.: **29/243,569**

* cited by examiner

(22) Filed: **Nov. 28, 2005**

Primary Examiner—Ralf Seifert

(74) Attorney, Agent, or Firm—Robert Platt Bell

(51) **LOC (8) Cl.** **02-07**(57) **CLAIM**(52) **U.S. Cl.** **D11/200**

The ornamental design for a buckle guard, substantially as shown and described.

(58) **Field of Classification Search** ..... D11/200–201, D11/206–210, 214–216, 218; 24/163 R, 24/169–171, 173, 177–179, 191, 194, 195, 24/200, 197; 280/801.1

See application file for complete search history.

FOREIGN PATENT DOCUMENTS

GB 2 307 505 5/1997

FIG. 1 is a left side elevational view of the buckle guard of the present invention.

FIG. 2 is a right side elevational view of the buckle guard of the present invention.

FIG. 3 is a rear elevational view of the buckle guard of the present invention.

FIG. 4 is a front elevational view of the buckle guard of the present invention.

FIG. 5 is a bottom view of the buckle guard of the present invention.

FIG. 6 is a top view of the buckle guard of the present invention.

FIG. 7 is a first perspective view of the buckle guard of the present invention from the right rear, with the apparatus inverted; and,

FIG. 8 is a second perspective view of the buckle guard of the present invention from the front left side.
